CHARLES SIEGFRIED, OF GENEVA, SWITZERLAND, ASSIGNOR TO THE FIRM OF LES FRÈRES BRÉGUET, OF GENEVA, SWITZERLAND

DIE HOLDER FOR WIRE-DRAWING BENCHES

Application filed March 13, 1929, Serial No. 346,676, and in Switzerland December 15, 1928.

This invention relates to improvements in cooling means for die-holders of a wire-drawing bench for very fine wires and consists in giving the die-holder the shape of a tube closed on every side and into which water under pressure is introduced.

It has been known that in order to obtain very high speeds with very fine wires it is necessary to provide a good cooling of the dies and the wire. This cooling must be intense and must be extended also to the drawing-rollers. For this purpose the dies and the rollers were frequently immersed into water where the moving rollers and the moving wire had to care for the moving of the water and for their cooling. But with this arrangement the speeds needed for an economical working of the very fine wires were not attained.

Now it has been found that in this respect very good results could be obtained by giving to the die-holder the shape of a tubular chamber having small outlet openings into which water under pressure is introduced.

Preferably this tubular chamber is made in two parts one part being formed as a cover. This cover may be slid over the freely exposed dies and will partly cover the slits provided for the wires.

The annexed drawing represents as an example a working form of a die-holder for wire-drawing benches according to the present invention.

Fig. 1 shows the general arrangement of the drawing rollers and of the die-holder.

Fig. 2 is a view of the same parts turned through 90° the die-holder being shown partly in section.

Fig. 3 represents a top view of the closed die-holder and

Fig. 4 shows how it can be held open for introducing the wires.

The leading drawing-roller *b* is arranged above the idle drawing-roller *c* and both rollers are mounted on the frame *a* represented only in part. The step rollers *b* and *c* are shown here with divergent axes the leading shaft being horizontal and the idle shaft being inclined. This arrangement of stepped rollers which tends to have the wires run-

ning up from the idle roller against the next higher step of the leading roller and obliquely to the direction of rotation of the latter roller so as to describe a spiral thereon in order to prevent a locally limited wear, is already known and does not form any part of this invention. It will not interfere with the wear of the dies. Between the rollers a die-holder *d* is fixed by the screws *e*. This die-holder is shaped like a tube closed on every side and curved according to the stepped outline of the drawing rollers. Its cross-section is best seen from Fig. 2. The dies *f* are placed on supports *g* joined by casting to the inside of the standard and are arranged along a curve which corresponds to the stepped outline of the drawing-rollers as shown especially in Fig. 3. This die-holder is made in two parts, a standard *g* and a cover *i*, both having a U shaped cross section and fitted together so as to form a closed tubular body. The standard *g* held fast by the framing possesses in its side walls located so as to constitute the top and bottom walls the slits *h* required for introducing the wires. The cover *i* possesses two lateral grooves *k* into which are slidably fitting corresponding ledges *s* of the standard so that the cover may be pushed into the position represented in Fig. 4 in order to open the die-holder. The die-holder *d* communicates by means of an opening *l* with a water inlet *m* in the framing *a*. The passage way *l* is dimensioned so that its cross section is larger than the sum of all water passages left partly open by the slits.

In the closed position, that is the position represented in Fig. 3, the water is admitted under pressure to the die-holder during the drawing process. This water spouts from the different openings left still open and cools the dies and the wires on every side. Further the sprays of pressure water from the slits will hit the lower drawing-roller as well as the upper drawing-roller and will take care of the lubricating needed there.

Instead of having a sliding cover the die-holder could also be provided with a hinged cover.

What I claim as new is:

Improved cooling arrangement in the die-holder of a wire-drawing bench for very fine wires, comprising a framing, a set of leading drawing rollers and a set of idle drawing rollers having their axes mounted on said framing one above the other, a die-holder forming a closed vessel fixed to said framing between the two sets of drawing rollers and comprising a curved semi-tubular standard and a semi tubular cover-plate both of U shaped cross-section and closed at both ends, the first having a base plate attached to the framing and ledges in its side walls fitting into corresponding grooves of the second and both, when fitted together, forming a closed vessel, slits for receiving the wires provided in both side walls of the standard and arranged in a curve so as to correspond with the stepped outline of the drawing rollers, supports cast to the inside of the standard and arranged to maintain the dies registering with the slits, a pressure water supply, a pressure water inlet connected therewith and with the framing and an orifice provided in the base plate and registering with said inlet and having a cross section larger than the sum of the openings formed by said slits so as to have water spouts formed 30 directed against the adjacent drawing rollers.

In testimony whereof I affix my signature.
CHARLES SIEGFRIED.
